UNITED STATES PATENT OFFICE.

KARL R. SCHUSTER, OF NEW YORK, N. Y.

CONCRETE-MIXER.

1,111,974,

Specification of Letters Patent.

Patented Sept. 29, 1914.

Application filed April 25, 1914. Serial No. 834,335.

To all whom it may concern:

Be it known that I, KARL R. SCHUSTER, a citizen of the United States, residing in the city of New York, borough of Brooklyn, county of Kings, and State of New York, have invented a certain new and useful Concrete-Mixer, of which the following is a specification.

This invention is a concrete mixer characterized by important advantages over machines common in the art, wherein the mixtures of the ingredients are effected by stirring them mechanically.

The objects in view are to expedite the operation of mixing the constituent parts of concrete or other materials; to thoroughly combine the materials; to enable the mixing operation to be carried on successfully during cold weather; to facilitate the operations of charging the materials into the machine and of discharging the resulting mixture therefrom; and to simplify the structure to the end that it is durable and efficient in operation and economical of manufacture.

Broadly stated, the invention embodies a tiltable container equipped with means for supplying air, gas or steam, to the interior thereof, whereby the constituents of the concrete or other mass are agitated by the pressure of aeriform fluid, said container being movable bodily to one position for receiving the materials and being movable, also, to another and different position for discharging the mixed mass.

In addition to the novel structure thus briefly outlined, the mixer is characterized by the use of several important features, viz:—The means for supplying air, steam or gas to the container are movable with said container so as to be normally in operative relation thereto; the flow of the fluid is controlled by a normally closed valve which is opened automatically when the container is moved, after charging, into a normal position, thus admitting the fluid at the time required to effect the agitation of the ingredients; a cover coöperates with the container in order to preclude the fluid admitted by the valve from ejecting or blowing out the ingredients, but at the same time the air or gas is free to escape from the container through a suitable vent so that the container is not sealed at the period of admitting the agitating agent, or in fact at any other

period; and means are provided for distributing the agitating fluid in different directions at the bottom of the container.

The machine is especially well adapted for mixing concrete, the coarse aggregate of which may be stones of any practicable size. The fluid pipe and valve cannot become obstructed by stones or other large pieces which may find their way into the container. The machine is so simple that the possibility of break-downs is very remote, and it is economical of manufacture.

An important advantage is the availability of steam, or other heated gas, as the agitating agent, whereby the materials are heated to a certain extent simultaneously with the mixture thereof. This makes it practicable to make concrete in low temperatures and during cold weather, in which respect the ordinary mechanical mixers are useless.

Other features and advantages of the invention will appear in the course of the following detailed description.

In the drawings, Figure 1 is a side elevation of a mixer embodying my invention, the full lines illustrating the mixing position of the container, one of the dotted lines showing the charging position of said container and the other dotted line illustrating the discharging position of the container. Fig. 2 is a vertical section, partly in elevation, the plane of the section being indicated by the dotted line 2—2 of Fig. 1. Fig. 3 is a horizontal section through the operating mechanism for opening the valve when the container assumes the upright position wherein the materials are mixed. Figs. 4 and 5 are detail sectional views, partly in elevation, illustrating different forms of deflectors by which the agitating fluid is directed in different paths within the lower part of the container. Fig. 6 is a side elevation of another embodiment of the invention wherein the cover is movable with respect to the container. Fig. 7 is a sectional view on the line 7—7 of Fig. 6.

A designates a container, herein shown as a vessel comprising an upper cylindrical part *a* and a lower conical part *a'*. The vessel is open at its upper end and it is mounted for tiltable movement by trunnions *b* *b'* secured to the opposite sides of the vessel above the conical part *a'* thereof. The trunnion *b* is solid, whereas the other trunnion *b'*

b' is tubular so as to produce a passage *c*. The trunnions are supported in bearings *c'* provided on a supporting frame, herein shown as consisting of side members *B* attached to a base *B'*. One of the side members is provided with a bracket *d* to which is attached the casing *e* of a valve *E*, said valve being herein shown as a turning or plug valve although it is evident that any other form of valve may be employed. The valve body *e* is provided with a passage *e'* for the flow of steam, air or gas through the valve when the latter is opened. Suitable means are provided for coupling a pipe or hose to the valve body, but as the details of this part of the structure may be varied within wide limits, I have not considered it necessary to illustrate the pipe or hose for feeding air, gas or steam to the container.

C is a pipe attached to the container so as to be movable therewith. As shown, this pipe is positioned exteriorly to the conical part *a'* of the container, the lower end of said pipe having an elbow *c''* which is attached to the lower extremity of said conical member *a'* forming a part of the container *A*. The upper end of the pipe *C* is attached to trunnion *b'* so as to communicate with the passage *c* therein. The body *e* of the valve is connected with the hollow trunnion *b'* by a pipe *D*, one end of which is attached to the valve body *e* so as to communicate with the passage *e'* therein, whereas the other end of said pipe *D* is received within the passage *c* of the hollow trunnion. A stuffing box *D'* is provided between trunnion *b'* and pipe *D* so as to minimize the leakage of the agitating fluid which is supplied from the valve through the hollow trunnion to the pipe *C*.

It is apparent that the pipe *C* is attached to the tank and the hollow trunnion for movement therewith when the hopper is tilted either to the charging position or to the discharging position, whereby the pipe is retained at all times in an operative relation to the tiltable container. Provision is thus made for supplying the agitating fluid to the lower part of the container when the valve *E* is open; but normally this valve is closed in order to cut off the flow of the agitating fluid into the container, said valve being opened only when the container assumes the upright position of Figs. 1 and 2 subsequent to the deposit of the materials within said container.

Suitable means are provided for imparting a tilting movement to the container. While various devices may be used for this purpose it is preferred to employ hand-operated mechanism illustrated in Fig. 2. The solid trunnion *b* extends through its bearing *c'* in the frame and to the protruding end of this solid trunnion is secured an internal gear segment *F*, the same being

shown as having a flange *f* provided with gear teeth on the inner edge thereof. With this internal gear segment meshes a pinion *F'*, the same being secured to a short *f'* which is provided with a hand-crank *F''*, said short shaft being journaled in a bearing of a bracket or hanger *f''* secured firmly to one of the side members *B* of the main frame.

G designates a cover which is separate from the container *A* and is supported in a fixed position on the upper part of frame *B*. The cover closes the open upper end of the container when the latter is in the upright position shown in the drawings, the main function of said cover being to prevent the materials from being blown out of the container by the pressure of the agitating fluid admitted by the pipe *C* to the lower part of said container. The cover is separate from the container and is supported by the frame so that the container is free to move on the axis afforded by the trunnions without changing the position of the cover. Said cover is shown as consisting of an arc-shaped piece of metal the curvature of which is concentric to the axis of movement of the tiltable container. The upper open end of the container is curved on an arc concentric to that of the cover *G*, and when the container is in the upright position the upper edge of said container fits close to the under surface of the curved cover.

The container is not sealed when in the upright position and in coöperative relation to the cover but, on the contrary, said cover is provided with a vent opening *g* so that in the mixing position the container is open to the atmosphere. This vent *g* is surrounded by a vent tube *G'* within which is secured a baffle *g'* which is positioned directly over the vent opening *g*. It is apparent that the air or steam supplied to the lower part of the container is free to escape through the opening *g* and the tube *G'*, but the cover *G* and the baffle *g'* minimize the outflow of any of the materials present in the container under the pressure of the agitating fluid supplied by pipe *C* to the bottom part of the container.

While various forms of means for automatically opening the valve may be employed, I prefer the mechanism shown in Figs. 1, 2 and 3 of the drawings. One of the side frames *B* is provided with a bearing *h* for a horizontal rockshaft *H* the ends of which project beyond the bearing. At one end of this rockshaft is secured a lever arm *I* by means of a key *i*, said lever arm being provided with an anti-friction roller *i'* which is in the path of a cam plate *K*. Said cam plate is fixed in any suitable way to the outside of container *A*, said plate being shown as having inclined edges *k* and an operative top edge *k'*, as shown in full and

dotted lines in Fig. 1. On the other end portion of the rockshaft H is secured another lever arm J , the latter being made fast with the rockshaft by a key j , said lever arm J being provided with a bent end j' . Fitted loosely on the rockshaft is an arm L which is positioned quite close to the lever J so that the bent end j' of said lever J will contact with the loose arm L . This arm L is attached to a depending valve rod M , the lower end portion of which is pivoted by a pin m to a crank arm m' of valve E . Said valve is held normally in a closed position by a spring O , one end of which is fastened 10 to a lug o of the valve rod M , whereas the other end of said spring is anchored on the frame by a fixed pin o' , said spring acting to normally depress the valve rod M and thereby turn the crank arm m' to a position 15 for closing valve E .

The elbow end of c^2 of the pressure pipe C is connected in any suitable way with the lower extremity or apex of conical section a' forming a part of the tank or container. Said pipe may be so positioned that the air, steam or gas will point toward the center of the mass or the pipe may discharge the agitating agent toward one side of the tank, as shown in Fig. 2. Furthermore, a deflector P may be positioned within the lower portion of the tank and opposite to the outlet from the pipe, said deflector consisting of members spaced to produce openings p , as shown in Fig. 4, whereby the deflector 25 acts to distribute the inflowing steam or air in different directions within the tank. Again, the deflector Q may be positioned within the lower part of the tank opposite to the outlet from the pressure pipe, as shown in Fig. 5, said deflector Q having 30 downwardly converging side walls which are substantially parallel to the walls of the container bottom a' . These different modes of directing the inflowing agitating agent so 35 distribute the steam or air as to attain the best results in making mixtures of aggregates of various sizes or weight.

The operation is as follows:—The container or tank A is turned to the dotted line 40 position toward the left in Fig. 1 in order to swing its open upper end beyond the closure G , at which time the materials to form the mixture are dumped or otherwise deposited into the container. The container having 45 been charged it is swung back to the upright position beneath the closure G , as shown in full lines in Figs. 1 and 2, and during this movement of the container one edge k of cam K contacts with the roller i 50 of lever I , thereby rocking shaft H and turning lever J so its bent end j engages with the loosely mounted arm L . This arm is operated during the return movement of 55 the container to the upright position for the purpose of lifting the rod M against the

tension of spring O , whereupon the arm m' is turned and valve E is opened, thus admitting the agitating agent under pressure (steam, air or gas) to the interior of the container and at the lower or bottom portion thereof, whereby the valve is opened automatically when the charged container returns to a normal position below the cover. The steam or air is thus supplied to the lower part of the container so as to flow upwardly through the materials therein, and as a result of this operation the materials are agitated to such an extent as to mix them thoroughly within a very short space of time. The inflowing agitating agent has a tendency to lift the materials within or blow them out of the container through the upper open end thereof, but the escape and waste of the material is precluded by cover G and baffle g' within the vent tube G' , said vent tube affording a free outlet at all times for the agitating agent supplied to the container. The materials having been mixed the container is turned in an opposite direction and to a discharging position, as indicated by the dot and dash lines in Fig. 1, whereby the mixed material is discharged through the open end of the container, said material flowing by gravity from the container. The operator now turns the gear in an opposite direction so as to restore the container, first, to a normal position below the cover and then to swing the container to the charging position indicated in dotted lines, but during the return movement of the container the valve mechanism is not operated, for the reason that the other edge k of cam K acts on the arm I and shaft H so as to turn the bent end of arm J away from the loosely mounted arm L which controls the valve, as a result of which operation the return of the container to a charging position withdraws arm J to a position where it will not act upon the valve mechanism so as to open 105 said valve. The container having been returned to a charging position the operations of depositing material therein and of mixing and discharging said materials are renewed.

It will be understood that any suitable agitating agent may be supplied to the interior of the container, for the purpose of mixing the materials therein. In this connection it is desired to call attention to the fact that steam or other heated agent may be supplied to the mixer for the purpose of mixing and heating the materials in low temperatures. This is particularly useful in preparing and installing concrete during cold weather, under which conditions the ordinary mixer cannot be used to advantage.

In the machine hereinbefore described, the cover G is supported in a fixed position on 130

the frame so that the container is movable relative thereto; but when the invention is to be embodied in a machine of increased capacity, a larger container is employed, it being desirable to increase the cross sectional area of said container rather than the vertical dimensions thereof. Under such circumstances, it is preferred to employ a cover which, instead of having a fixed relation to the container, is mounted for movement with respect to said container. Accordingly, the cover G' of Figs. 6 and 7 is supported for movement simultaneously with the container, and preferably the cover swings in an opposite direction to that in which the container itself moves. Said cover G' is carried by parallel arms S S' which are fitted loosely on the trunnions b b' of the container, one of said arms being formed with a gear segment T. The trunnion b' is provided with another gear segment T', the latter being in opposing or facing relation to the segment T. A shaft V is journaled in a suitable bearing on the side frame B, said shaft being positioned intermediate the facing gear segments T T', and secured rigidly to this shaft is a gear pinion U' the teeth of which are in mesh with the gear segments as shown. Suitable means are provided for operating the shaft; a hand crank is shown for this purpose, although it is evident that the shaft may be turned by power if desired.

It is apparent that by turning the shaft U in one direction, the gear segments T T' will be turned simultaneously and in opposite directions to each other, and thus the movement of the container in one direction and to a charging position will result in a movement of cover G' in an opposite direction so as to fully uncover the open end of the container and permit the materials to be deposited therein. Of course, the backward movement of the container to a mixing position will be followed by a return of the cover G' to a position over the container so as to prevent the materials from being blown out of the container when the agitating agent is admitted thereto.

In all other respects the mixer of Figs. 6 and 7 embodies the several features of the invention as herein shown and described.

Having thus fully described the invention, what I claim as new, and desire to secure by Letters Patent, is:

1. A mixer embodying a pivoted container movable to a charging position and to a discharging position, and valve-controlled means for supplying an aeriform mixing agent to the lower part of said container.

2. A mixer embodying a tiltable container and valve-controlled means unitary therewith for supplying air, steam or gas to the interior of said container and at the

bottom portion thereof, said container being movable to a charging position and to a discharging position without disconnecting said supply means.

3. A mixer embodying a tiltable container, means for supplying an agitating agent under pressure to said container, and a cut off controllable by the tilting movement of the container for opening and closing said supply means. 75

4. A mixer embodying a pivoted container open at the upper end, means for supplying an agitating agent under pressure to said container, and a closure for said open end of the container, said container being movable relative to said closure. 80

5. A mixer embodying a pivoted container open at the upper end, means for supplying an agitating agent to said container, and a closure for said open end of 85 the container, said closure being provided with a normally open vent, whereby the closure prevents the materials from being blown out of the container by the action of said agitating agent and the latter is free 90 to escape through said vent, said container being movable relative to the closure for assuming charging or discharging positions.

6. A mixer embodying a pivoted container, means movable with the container 95 for supplying an agitating agent to the interior of said container, and valve mechanism controllable by the movement of said container for admitting the agitating agent thereto when it occupies a substantially upright position. 100

7. A mixer embodying a container provided with trunnions for pivotally supporting it, one of said trunnions being hollow, and a pressure pipe connected with said hollow trunnion and with the bottom portion of said container so as to supply an agitating agent through said hollow trunnion and the pipe to the interior of the container at the bottom portion thereof. 110

8. A mixer embodying a container provided with trunnions for pivotally supporting it, one of said trunnions being hollow, a pressure pipe connected to said hollow trunnion and to the container for supplying an agitating agent to said container, and a valve operable by the pivotal movement of said container for controlling the flow of the agitating agent to said container. 115

9. A mixer embodying a tiltable container, means unitary with said container for supplying thereto an agitating agent under pressure, said container being movable from a mixing position to a charging position and to a discharging position, a 120 valve for controlling the flow of the agitating agent to said container, and operating means for said valve, said operating means being actuated by the movement of the container from its charging position to a 125 discharging position. 130

mixing position and being idle when the container moves into and out of its discharging position.

10. A mixer embodying a tilttable container, means unitary with said container for supplying thereto an agitating agent under pressure, said container being movable from a mixing position to a charging position and to a discharging position, a valve for controlling the flow of the agitating agent to said container, and valve operating means including a cam movable with the container and a plurality of levers one of which is connected with the valve and another is in the path of said cam:

11. A mixer embodying a tilttable container, movable to a charging position and to a discharging position, valve-controlled means unitary with said container for supplying thereto an agitating agent under pressure at a period when said container occupies a position intermediate said charging and discharging positions, and means for distributing the agitating agent in different directions within the container.

12. A mixer embodying a tilttable container movable successively to charging and discharging positions, valve-controlled means unitary with said container for supplying thereto an agitating agent under pressure at a period when said container occupies a mixing position intermediate said charging and discharging positions, and a deflector positioned opposite to the outlet from said supply means for distributing the agitating agent in different directions within said container.

13. A mixer embodying a tilttable container movable successively to charging and discharging positions, valve-controlled means unitary with said container for supplying thereto an agitating agent under pressure when said container is in a mixing position intermediate said charging and discharging positions, and a baffle positioned within the container and over the outlet from said supply means for precluding the entry of materials into the supply means.

14. In a mixer, the combination of a tilttable container open at the upper end, a closure for said open end of the container, said closure being disconnected from the container and the latter being movable relative to said closure for assuming charging and discharging positions, said closure having a normally open vent, an inlet pipe for supplying an agitating agent to the bottom por-

tion of said container, and a baffle in the path of the agitating agent escaping from the vent.

15. In a mixer, the combination with a tilttable container, and a pressure pipe connected therewith, of a valve for controlling the flow of an agitating agent through said pipe, a rock arm linked to the valve, a valve operating member on the container, a second rock arm in the path of said valve operating member, and a third arm operated by the movement of the second rock arm and coöperating with the first rock arm for opening the valve when the container moves from the charging position to the mixing position.

16. In a mixer, the combination with a tilttable container and means for supplying an agitating agent thereto, of a closure for said container, said closure being movable simultaneously with the movement of the container.

17. In a mixer, the combination with a tilttable container and means for supplying an agitating agent thereto, of a pivotally supported closure for said container, and means operating to impart movement to the closure simultaneously with the tilting movement of the container.

18. In a mixer, the combination with a tilttable container and means for supplying an agitating agent thereto, of a pivotally supported closure for said container, and operating means coöperating with the container and the closure for imparting movement to the closure in an opposite direction to the container and simultaneously therewith.

19. A mixer embodying a container pivoted for movement successively to charging and discharging positions, means unitary with said container for supplying a mixing agent thereto, and a cut off coöperating with said unitary supply means and controllable upon the pivotal movement of the container for admitting the mixing agent when said container is in a position intermediate the charging position and the discharging position.

In testimony whereof I have signed my name to this specification in the presence of two subscribing witnesses.

KARL R. SCHUSTER.
